(57) **CLAIM**

I claim, the ornamental design for a license plate frame, as shown and described.

DESCRIPTION

FIG. 1 is a perspective view of a license plate frame showing my new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines showing of portions of the license plate frame are for the purpose of illustrating environmental structure and form no part of the claimed design.

1 Claim, 5 Drawing Sheets
